GENERAL ELECTRIC COMPANY, A CORPORATION OF NEW YORK.

CAM AND ADJUSTING DEVICE THEREFOR.

1,104,637.

Specification of Letters Patent.

Patented July 21, 1914.

Application filed June 13, 1912. Serial No. 703,893.

To all whom it may concern:

Be it known that we, CHARLES DAY and GEORGE E. WINDELER, subjects of the King of Great Britain, and residing at Stockport, 5 Cheshire, England, have invented certain new and useful Improvements in Cams and Adjusting Devices Therefor, of which the following is a specification.

In setting up internal combustion engines, 10 particularly of the constant pressure type, it is necessary to position the fuel cams with great exactness. It is also necessary at times to change the position of these cams, either angularly or radially or both, to compensate 15 for wear on some part of the engine. For example, it may be necessary on account of the re-surfacing of the fuel valve, or on account of worn gears which drive the cam shaft. In these cases some adjustment of 20 the cams is necessary if the best results are to be obtained. Furthermore, it is important to so construct and arrange the parts that each cam can be quickly and easily 25 adjusted angularly or radially, as the case may be, by the engineer in charge of the plant, without requiring the services of a man specially skilled in the art. Also the nature of the adjusting means must be such that once the parts are adjusted, there is 30 no danger of their working loose and the cam taking an improper position.

Our invention has for its object to improve the construction of said cams whereby they may be quickly removed and replaced, 35 and also adjusted radially and angularly on their support to meet the requirements of the engine.

For a consideration of what we believe to be novel and our invention, attention is 40 directed to the accompanying specification and claims appended thereto.

In the accompanying drawing, which illustrates one of the embodiments of our invention, Figure 1, is a view in side elevation 45 of or support for a fuel cam of a constant pressure oil engine; Fig. 2 is a section of the cam taken on line 2—2 of Fig. 1 with the cam in place; Fig. 3 is a sectional view of the support taken on line 3—3 of Fig. 1; Fig. 4 is a view in side elevation of the cam and its support; Fig. 5 is a perspective view 50 of the swivel blocks; Fig. 6 a perspective of a spacer used in adjusting the cam angularly; Fig. 7 shows a cover plate for the blocks and spacers in side elevation and on

edge; Fig. 8 is a sectional view of the removable cam; Fig. 9 is a view in side elevation of the cam; Fig. 10 is a perspective view of the cam swivel block, and Fig. 11 a perspective view of a spacer used in adjusting 60 the cam block radially.

12 indicates the cam shaft and mounted thereon and secured by a key is a hub or cam support 13, the latter having an annular surface 14 and a flange 15, said flange 65 may, if desired, also form a cam that does not require adjustment, and in this manner the number of parts is reduced. The cam proper comprises two principal parts, a ring 16 whose peripheral surface is concentric 70 with the axis of the shaft and a removable cam block 17 whose face is of the proper shape and dimensions to open and close the fuel valve of the engine at the proper time and by the proper amount. The ring 16 is 75 snugly fitted on the annular surface 14 but is capable of being adjusted angularly thereon. It is provided with a peripheral recess having shoulders 18 to engage the ends of the block; also with a cut-away portion or 80 side recess to receive the part 20 of the cam block. Mounted on the support is an axially extending stud bolt 21 that fits into a concentric slot 22 in the ring 16. On the end of the bolt is a washer and clamping nut. The 85 support also carries a stud 23 that is provided with a squared portion 24 which fits into a concentric slot 25 formed in the ring and having curved ends.

It is necessary to accurately position the 90 cam with respect to the fuel valve lever; it is also highly desirable to provide a simple means whereby the cam can readily be set in the first instance or reset thereafter when the conditions of operation require it. To 95 this end the slot 25 has rounded ends formed by drilling out the stock in the blank. The stock between the holes is then cut away leaving a segmental opening. In the ends of the opening are mounted swivel blocks 26, 100 Fig. 5, which are flat on one side and curved to correspond to the end of the opening on the other. The blocks are free to adjust themselves angularly. Between the blocks and the squared portion 24 of the stud 23, 105 are located thin flat plates or shims 27, Fig. 6. These are carefully made of different thicknesses so that many adjustments can be obtained by inserting them on one side of the stud or the other. The stud is made 110

square where the plates engage it to present a large surface, so that the danger of the parts wearing and permitting lost motion or play is avoided, and to permit of the 5 parts being solidly united. Owing to the use of the self-adjusting swivel blocks in the rounded ends of the groove, the plates or shims can be made of stock of uniform cross section, that is to say, have parallel front 10 and rear faces. Without this, or an equivalent arrangement, they would have to be thicker on one side than the other. In other words, segmental in shape which would be relatively costly to make and fit. 15 The blocks and plates constitute metal fillers which are substantially solid and just fit the slot 25 and are confined in place by the cover 30, Fig. 7. The cover is held in place by the stud 23 and its clamping nut. In the 20 ring are spanner holes 31, Fig. 1, by means of which the cam ring can be angularly adjusted when the nuts on the studs are loosened or removed and some of the shims taken out. 25 Referring now to the cam block, it is best shown in Figs. 4, 8 and 9. The periphery of the block may be given any desired shape. As shown it has two inclined faces that gradually rise from the periphery of the 30 ring 16 and are connected by a rounded surface 32, said block being hardened to reduce wear. As the cam block moves under the fuel valve lever, said valve is opened and closed. It is sometimes necessary to change 35 the radial position of the cam block due to wear of some engine part, or for some other cause. To this end the block is provided with a flange portion 20 that extends perpendicular to its face. In said portion is a 40 slot 33 having parallel sides, a flat inner end and a curved outer end. In the outer end is mounted a swivel block 34 having a curved surface conforming to the shape of the slot and in the lower end are one or more plates 45 or shims 35, the arrangement being similar to that previously described. The block is held in place by the end shoulders 18, Fig. 1, the side walls 36 formed on the ring which takes the thrust, and the stud bolt 37, 50 Figs. 2 and 4, which holds it against the flat face of the ring. This bolt has a squared portion where it passes through the radial slot 33. Obviously by changing the 55 number of shims on one side or the other of the bolt the block as a whole can be adjusted radially in or out. The bolt is provided with a nut having small groove 38 to receive a cotter pin to prevent it from turning. 60 It will thus be seen that our improved cam and its adjusting means are simple in the extreme and that the adjustments, no matter how small or large they may be, can be accurately made by a person of ordinary skill. 65 As a general proposition it may be said that

the cam block will be adjusted radially when the engine is first fitted up, and that it will be adjusted angularly to compensate for wear of the engine parts at subsequent times

By the constructions outlined it will be 70 observed that all moving parts of the adjustments have a substantially solid metal bearing, thus entirely relieving the securing means of shocks which tend to loosen them.

In accordance with the provisions of the 75 patent statutes we have set forth what we believe to represent the best embodiment of our invention, but it is to be understood that the drawing is only illustrative and that our invention can be carried out by other means. 80

What we claim as new and desire to secure by Letters Patent of the United States is:—

1. Means for adjusting a cam, consisting of a shaft, a hub fixed thereto, a ring carried by the hub and concentric with the shaft, said ring having slots therein, studs fixed in the hub and passing through the slots, metal fillers between the studs and the ends of the slots, means for holding the fillers in place, and a cam block carried by the ring. 85

2. Means for adjusting a cam, consisting of a shaft, a hub fixed to the shaft, a ring carried by the hub and concentric with the 90 shaft, said ring having slots therein, studs fixed in the hub and passing through the slots, metal fillers between the ends of the slots and the studs with means for holding them in place, a cam block, shoulders on the 100 ring between which the cam-block is radially adjustable, a radial slot in the block, a bolt passing through the slot and seated in the ring, metal fillers in the slot and means for holding them in place; whereby 105 the circumferential and radial adjustment of position of the cam may be effected in such manner that when fixed in position shocks upon the cam are not transmitted to its securing means, as described. 110

3. In combination, a support, a cam mounted thereon which is provided with a segmental slot, a means that passes through the slot into the support for holding the cam, flat shims between the means and the 115 ends of the slot, and a swivel block between the shims and one end of said slot.

4. In combination, a support, a cam mounted for angular adjustment thereon which is provided with a segmental round 120 ended slot, a clamping bolt that has flat surfaces where it passes through the slot, swivel blocks located in the ends of the slot, and removable shims located between the blocks and the flat surfaces of the bolt. 125

5. In combination, a support, a cam mounted for angular adjustment thereon which is provided with a segmental round ended slot, a clamping bolt that passes through the slot, swivel blocks located in the ends of 130

the slot, a plurality of thin shims having parallel front and rear surfaces located between the bolt and blocks, and a retaining device for preventing the block and shims 5 from getting out of place.

6. In combination, a ring that is provided with a shouldered recess on its periphery, a cam block mounted in said recess which is provided with a radial slot, a bolt that extends through the slot and has flat faces and a swivel block located in one end of the slot 10 and a shim in the other which embrace the bolt on two sides and hold the block against radial movement.

7. In combination, a ring that is provided 15 with a shouldered recess on its periphery and one side, a cam block that is fitted into both of said recesses and is provided with a slot, a bolt that extends through the slot, and a swivel block and shim that are located 20 in the slot between its ends and said bolt.

In witness whereof, we have hereunto set our hands this 23rd day of May, 1912.
